UNITED STATES PATENT OFFICE

120,501

DESIGN FOR A COMMERCIAL PHONOGRAPH

William F. Feyrer, Norwalk, Conn., assignor to
Dictaphone Corporation, New York, N. Y., a
corporation of New York

Application February 23, 1939, Serial No. 83,152

Term of patent 14 years

To all whom it may concern:

Be it known that I, William F. Feyrer, a citizen of the United States and a resident of the town of Norwalk, county of Fairfield, and State of Connecticut, have invented a new, original, and ornamental Design for a Commercial Phonograph, of which the following is a specification, reference being had to the accompanying drawing, forming part thereof.

The figure is a front perspective view of a commercial phonograph, showing my new design.

The rear and left-hand walls of the phonograph are plain and unornamented.

I claim:

The ornamental design for a commercial phonograph, as shown and described.

WILLIAM F. FEYRER.
